FIG. 3.

FIG. 2.

Inventor:
Emile Raymond Kochlin
per H. W. Blucker
Attorney.

UNITED STATES PATENT OFFICE.

EMILE RAYMOND KOECHLIN, OF AMSTERDAM, NETHERLANDS, ASSIGNOR TO
NAAMLOOZE VENNOOTSCHAP WEDUWE J. AHREND & ZOONS INDUSTRIE- EN
HANDELSVEREENIGING, OF AMSTERDAM, NETHERLANDS, A COMPANY OF
THE NETHERLANDS.

DRAWING-TABLE.

1,341,988.

Specification of Letters Patent. Patented June 1, 1920.

Application filed October 5, 1918. Serial No. 257,937.

To all whom it may concern:

Be it known that I, EMILE RAYMOND KOECHLIN, a subject of the Queen of the Netherlands, residing at Amsterdam, in the 5 Kingdom of the Netherlands, have invented certain new and useful Improvements in Drawing-Tables, of which the following is a specification.

My present invention relates to drawing 10 tables and is more particularly applicable to drawing tables of the type comprising a drawing board connected with two adjacent joints of an articulated parallelogram guide the third joint of which forms a fixed fulcrum and is connected with the board by a 15 link which extends beyond said fulcrum and is provided with a counterweight for counterbalancing the board, whereas the fourth joint is pivoted to a member whose freedom 20 of motion is counteracted by a suitable friction device.

My invention is designed to provide improved means for avoiding any undue 25 change in the form of the parallelogram guide as long as the board is normally used, but allowing at the same time the form of said link mechanism to be changed when desired by a comparatively slight pressure exerted on the board.

My invention will be best understood by 30 reference to the accompanying drawing, which will now be described, it being understood, however, that various changes may be made in the details of construction and 35 arrangement by those skilled in the art, without departing from the spirit and scope of my invention.

In the drawing:

Figure 1 is a side elevation of a drawing 40 table embodying my invention, Fig. 2 being a sectional view on a larger scale of that part of the drawing table which comprises the improved means, and Fig. 3 a cross-sectional view on A—A in Fig. 2.

Referring to the drawing, the numeral 1 45 designates the drawing board which is connected in a known manner with a parallelogram guide the joint 2 of which forms a fixed fulcrum, the joint 3 being hinged to a 50 rod or arm 4 which is slidably mounted in a tube 6 having its pivot at 5.

Secured to the lever 7 carrying the counterweight 8 and concentric relative to the fulcrum 2 is a circular rod 9 passing through

a hole in a sleeve 10 secured to a cross-piece 55 11 between the legs 12 and 13 of the table, a cap 14 being screwed on said sleeve. Located within said sleeve is a helical spring 15 one end of which bears against the screw cap 14, the other end bearing against a brake 60 shoe 16. Said brake shoe 16, which normally contacts with the circular rod 9, is adapted to press said rod against a second brake shoe 17.

A screw bolt 18 which is provided with a 65 handle 19 and screwed through the cover of the cap 14, is adapted to be screwed into the sleeve 10 through a sufficient distance to press the brake shoe 16 against the rod 9 even if the cap 14 is turned back as far as 70 possible.

When using my improved drawing table I put the helical spring 15 under proper tension by means of the screw cap 14, whereby the rod 9 is gripped between the brake shoes 16 75 and 17, and I adjust this gripping force so that the rod 9 does not tend to slide within the sleeve 10 when I use the board in the usual manner, that is to say, as long as I am drawing, and that an increased pressure on 80 the board is required for causing a displacement of said rod. As a matter of course, this gripping force will be initially adjusted to suit the requirements, but, once adjusted, it should preferably be left unchanged. The 85 bolt 18 is normally screwed back so far that its end does not engage the brake shoe 16.

The arrangement described evidently prevents the board from being unduly displaced parallel with itself as long as it is normally 90 used, but it allows of this movement being effected, if desired, by an increased pressure exerted on the board.

Now, if I wish to firmly secure the rod 9 95 within the sleeve 10, for instance, if at any moment it should be desired to increase the load of the board, I turn the screw bolt 18 until the frictional resistance of the brake shoes 16 and 17 is increased to the required degree, which obviously can be done without 100 interfering with the position of the screw cap 14 relative to the sleeve 10. It will be readily understood that after unscrewing the bolt 18 the tension of the spring 15 will again be exactly the same as before, so that 105 the spring friction device does not require any readjustment.

Having thus fully described my invention,

I claim as new and desire to protect by Letters Patent of the United States:

1. In a drawing table, the combination of a drawing board, a support, a pivot on said support, a link connected to said board and to said pivot, a curved member concentric with said pivot and secured to said link, clamping means on said support for frictionally holding said curved member in the desired position, adjustable means for varying the friction exerted by said clamping means, and means operable at will to cause said clamping means to positively hold the curved member in the desired position.
- 5 2. In a drawing table, the combination of a drawing board, a support, a pivot on said

support, a link connected to said board and to said pivot, a curved rod concentric with said pivot and secured to said link, a sleeve secured to said support, said rod extending through said sleeve, a brake-shoe adapted to engage said rod, a cap in threaded engagement with said sleeve, a spring interposed between said shoe and cap, and a screw spindle in threaded engagement with said cap and adapted to bear against said shoe.

In testimony whereof I affix my signature.

EMILE RAYMOND KOECHLIN.
